 Philadelphia, Pa., a corporation of Delaware

Application May 25, 1937, Serial No. 144,733

8 Claims. (Cl. 179—171)

This invention relates to a novel amplifier for compensating for the non-linear characteristic of certain electrical signal devices or circuits. The principal object of the invention is to provide a novel amplifier having a non-linear characteristic which may be made to compensate for the non-linear characteristic of a device or circuit with which it is employed. The invention is useful, for example, in television systems and the like for the purpose of improving the contrast of the picture and to overcome certain inherent objectionable characteristics of the apparatus used to translate light images into electric signals and vice versa. In a conventional television system, the video signal is formed in a camera tube which produces an electrical signal that is proportional to the intensity of light at a particular point in the image and at a certain time. As the image is scanned, the output of the camera tube varies in accordance with the light intensity. It is desirable that the output signal of the camera tube be proportional to the actual light intensity but, unfortunately, in the camera tubes which are now available, the amplitude of the output signal tends to fall off during scanning of the high light portions of the image. In other words, while the camera tube has a substantially linear characteristic over a portion of its operating range, its characteristic tends to become non-linear over a portion of its range corresponding to the white portions of the image and, as a result, the amplitude of its output signal tends to fall off in that region. While the camera tube is the principal offender in this respect, the picture tube which translates the video signal into the desired picture has a similar tendency but to a lesser degree than the camera tube.

The present invention provides a novel wide band amplifier whose gain may be caused to increase over a particular portion of its operating range to impart to the amplifier a non-linear characteristic which is complementary to the non-linear characteristic of devices such as those above mentioned, and which may be employed to compensate for the non-linearity of such devices to obtain substantially linear over-all response therefrom. Thus, the invention may be employed to correct the non-linearity of a camera tube, in which case the gain of the amplifier provided by the invention is caused to increase in the region where the output of the camera tube tends to fall off. Another object of the invention is to provide such a non-linear amplifier which has a flat frequency response and which is capable of transmitting the wide range of fre-

quencies obtained in the video signal of a high definition television system.

Still another object of the invention is to provide such a non-linear system which has a substantially instantaneous response, i. e., one in which the gain of the amplifier at any instant is determined by the signal level at that instant and thus one in which the gain may be changed at a rate comparable with the highest frequency required to be transmitted.

The invention comprises essentially two units, viz. a variable-gain amplifier and a gain-control amplifier. The variable-gain amplifier is adapted to be included in the signal channel of the device whose characteristic is to be corrected, while the gain control amplifier is connected in a manner to derive a control signal from the signal channel and to supply such signal to the variable-gain amplifier so as to vary the gain thereof. The gain control amplifier may be connected so as to derive the control signal from a portion of the signal channel subsequent to the variable-gain amplifier, in which case the control signal is fed back to the variable-gain amplifier, or the gain-control amplifier may be connected so as to derive the control signal from a portion of the signal channel ahead of the variable gain amplifier. By these different modes of connection, different operating characteristics may be obtained, as described hereinafter.

In the case where the backward or feed-back connection is employed, regeneration is avoided by virtue of the fact that the variable-gain amplifier is so constructed that the control signal applied thereto cannot appear in the output circuit of the amplifier. In other words, the control signal cannot traverse the loop which is provided by the particular connections employed. The control signal serves only to control the gain of the variable-gain amplifier. This is a very important feature of the invention and it is, therefore, a further object of the invention to provide a novel amplifier which is not subject to instability due to regeneration.

Since the invention is particularly useful as a means to overcome the above-mentioned objectionable characteristics of a television system, it will be described herein with particular reference to such use. It will be understood, however, that the invention is not thus limited but is capable of use in any instance where it may be desired to compensate for non-linearity of a particular device or circuit.

In the accompanying drawings:
 Fig. 1 is a block diagram illustrating the back-

ward connection of the two units as above mentioned;

Fig. 2 is a similar diagram illustrating the forward connection of the two units;

Fig. 3 is a circuit diagram illustrating in detail a certain form which the invention may take;

Fig. 4 illustrates certain characteristics of the amplifier provided by the invention; and

Fig. 5 is a block diagram illustrating the application of the invention to a television system.

Referring to Fig. 1; the line 1 represents a signal channel through which the signal is passing in the direction of the arrowheads. A variable-gain amplifier 2 is included in the signal channel 15 as illustrated, while the gain-control amplifier 3 is connected to the signal channel and to the variable-gain amplifier, as illustrated, so that a control signal is derived from a portion of the signal channel subsequent to the variable-gain amplifier 20 and passes through the feed-back circuit including the gain-control amplifier, as indicated by the arrowheads.

In Fig. 2, the gain-control amplifier is connected so as to derive the control signal from a portion of the signal channel ahead of the variable-gain amplifier, so that the control signal traverses the control circuit including the gain-control amplifier as indicated by the arrowheads.

In Fig. 1, the control signal is first amplified 30 by the variable-gain amplifier and is then fed through the gain control amplifier and applied to the variable-gain amplifier. This serves to impart an exponential characteristic to the device. In other words, the amplification of the 35 signal traversing the variable-gain amplifier is approximately proportional to the amplitude of the amplified signal itself. On the other hand, in Fig. 2, the control signal is not amplified prior to its passage through the gain-control amplifier 40 and in this case, the gain of the variable-gain amplifier is proportional to the amplitude of the input signal and, consequently, the device has a square law characteristic. The device of Fig. 1 which has an exponential characteristic is preferred for the reasons set forth hereinafter.

The variable-gain amplifier may be of the type disclosed in my prior Patent No. 2,081,127, dated May 18, 1937. In Fig. 3, there is illustrated a specific form of a variable-gain amplifier of this type which may be employed. There is also illustrated a specific form of gain-control amplifier which is connected according to the method of Fig. 1. Referring to Fig. 3, the signal source E is representative of any means from which the input signal of the device may be derived. The signal is supplied to the control grids of tubes V₁ and V₂ in equal and opposite phase relation by means of the phase-inverter tube V₃. Such phase-inversion circuits are well known in the art and need not be described further. The variable-gain amplifier comprises essentially the four tubes V₁, V₂, V₄ and V₅. The cathodes of the tube V₁, V₂ and V₄ are commonly connected through a resistor R to ground. Thus, the resistor R is connected in the input and output 60 circuits of the tubes V₁, V₂ and V₄. It will be seen that any voltage appearing across the resistor R will be applied to the control grids of tubes V₁ and V₂. Any signal developed across the resistor R is, therefore, supplied in the same 65 phase to both of the tubes V₁ and V₂.

The output signal from tube V₁ has its phase inverted by the tube V₅ which may be coupled to tube V₁ by resistance-capacitance coupling as shown. The output of tube V₅ is combined with

the output signal from tube V₂ and the combined output signal is taken from across the common resistor R₁. It will be seen then that the tubes V₁, V₂ and V₅ are included in the signal channel and the opposite phase signals supplied to tubes V₁ and V₂ from tube V₃ are added together by virtue of the phase inversion of one of them and the combining of the signals as described. It will be apparent, however, that any signal appearing across resistor R, since it is applied to tubes V₁ and V₂ in the same phase, will not appear in the output circuit of the variable-gain amplifier 2. In other words, signals of like phase applied to tubes V₁ and V₂ are caused to oppose and neutralize each other in the variable-gain amplifier so that they do not appear in the output circuit of the amplifier. This is a very important feature of the device as discussed further hereinafter.

The gain-control signal is derived from the signal channel and supplied by the gain-control amplifier 3 to the input circuit of tube V₄, whose anode is connected directly to the anode supply source. Hence the voltage developed across resistor R will be essentially the same as the signal supplied to the grid of tube V₄. The tubes V₁ and V₂ preferably have identical characteristics and each of these tubes has the property that its mutual conductance is proportional to the voltage between its grid and cathode. The input signals supplied by tube V₃ are preferably small as compared with the total operating range of the tubes V₁ and V₂, and hence the gain of the variable-gain amplifier is determined and is substantially proportional to the voltage across resistor R which, of course, is determined by the voltage in the grid circuit of tube V₄.

The output signal of the variable-gain amplifier is the same as its input signal amplified, however, by an amount determined by the signal supplied to the grid of tube V₄. A variable-gain amplifier of this type has the important characteristic above mentioned, viz., that the control signal supplied to it produces no corresponding component in the output circuit but 40 serves solely to determine the gain of the amplifier. In the absence of an input signal, no output signal is produced by the amplifier regardless of any control signal supplied to tube V₄. When an input signal is present, the only effect of the control signal is to determine the amount by which the input signal is amplified. This characteristic of the variable-gain amplifier permits the use of the feed-back connection shown in Figs. 1 and 3 without incurring instability. Furthermore, the input circuit for the input signal and the input circuit for the control signal are effectively completely isolated one from another so that there is insufficient coupling between them to cause instability in a device connected as 50 shown in Fig. 2.

The gain control amplifier 3 may comprise tubes V₆ and V₇ as shown in Fig. 3. Where the device is used for transmitting signals covering a wide frequency range and including high frequency components, such as obtained in a television video signal, it will be found that potentiometer type gain controls are not satisfactory. A suitable gain control circuit may be obtained, however, by varying the bias on an amplifier tube of the remote cut-off type. Thus, the tube V₇ 65 may be of the remote cut-off type and may have the characteristic that its mutual conductance is variable and determined by its grid bias. The grid bias may be determined by a gain control 70

potentiometer G shunted by a bias battery. The movable arm of the potentiometer may be connected to the grid leak and preferably should also be grounded through a blocking condenser. 5 Varying the bias will vary the gain of amplifier stage including the tube V₇.

It will be noted that resistance-capacity coupling is employed throughout both amplifiers in order to obtain the desired uniform frequency 10 response range. Both amplifiers should be capable of transmitting the highest useful frequency component in the video signal and hence there will be no appreciable time delay between the signal in the transfer circuit of the variable-gain 15 amplifier and the signal in its gain control circuit. This instantaneous response characteristic, which is a desirable feature of the invention, would not obtain if filter circuits, inherent or otherwise, were employed to restrict the frequency 20 range of the signal supplied to the gain control circuit.

It will be understood that the two units may take forms other than those specifically disclosed. The variable-gain amplifier shown in Fig. 3 is 25 representative of any amplifier having the characteristics above described, that is a unit for amplifying one signal by an amount determined by a second signal and in which means are provided for preventing the transfer of the second signal 30 to the output circuit. The gain control amplifier illustrated is representative of any suitable gain-control device which may be employed for the purpose of the invention.

In Fig. 4, there are illustrated characteristic 35 curves illustrating the relation between the input and output voltages which are obtainable by employing an amplifier of this type. Curve A represents the desired linear relation, while curve B illustrates the normal characteristic of a camera tube of a television system. It will be seen that in 40 the region near the origin O, the output voltage is approximately proportional to the input which, in the case of the camera tube, would be the illumination of the image being scanned. It will be seen from curve B, however, that as the amount 45 of illumination increases, the output voltage does not increase proportionately but falls off somewhat. This may be overcome by providing a non-linear amplifier in accordance with the present invention in which the output voltage increases 50 more rapidly than the input voltage for the region away from the origin O, as illustrated by curve C. Where the characteristic C is required, as in the case of a camera tube, the polarity of the 55 control signal supplied to the gain-control amplifier should be such that, as the signal traversing the amplifier changes in response to an increase in light intensity, the gain of the amplifier likewise increases. The amount by which the 60 curve C departs from the linear characteristic A may be determined by the gain of the amplifier. In the device of Fig. 3, the gain of the amplifier may be controlled by the gain-control device G.

As described above, a device of the type shown 65 in Fig. 1 has an exponential characteristic, while a device of the type shown in Fig. 2 has a square law characteristic. The difference between these characteristics resides largely in the fact that the exponential characteristic corresponds more closely to a linear characteristic near the origin 70 of the curves and diverges more rapidly from the linear characteristic away from the origin than does a square law characteristic. While the difference between these two characteristics is not very marked for the operative region in which

the device is used, nevertheless it has been found that the exponential characteristic is preferable and should preferably be employed. For this reason, a device of the type shown in Fig. 1 is preferable to that shown in Fig. 2. 5

In Fig. 5, there is shown a block diagram embodying the essential elements of a television receiver which employs the device of the present invention. While the device of the invention may be used at either the transmitter or the receiver, 10 it is preferably employed at the receiver in order that it may serve the additional useful purpose of minimizing the range of modulation required to transmit effectively a given number of shades in an image being televised. 15

As shown in Fig. 5, a television receiver employing the device of the invention may comprise a unit 4 which, when supplied with television signals, produces a video signal and also the proper deflecting signals for the picture tube 5. 20 The video signal may be supplied to the variable-gain amplifier 2 and the output of this amplifier may be supplied to a second video amplifier 6 and thence to the picture tube. A control signal may be derived from the output of the amplifier 25 6 and fed back through the gain-control amplifier 3 to the variable-gain amplifier, as above described.

A television receiver embodying the device of the invention is characterized by improved clarity 30 of the received image and by the fact that the image contains a larger number of light gradations or shades than it has been possible to obtain in prior devices. Generally speaking, it has been found that by employing the device of the 35 present invention, the number of distinguishable light gradations or shades may be increased by approximately 20 to 25%. It will be apparent, therefore, that a marked improvement in the 40 performance of apparatus, such as television apparatus, which has heretofore had the objectionable characteristics above mentioned may be obtained by employing the present invention.

As indicated above, the invention contemplates broadly the provision of a variable-gain amplifier, 45 the gain of which may be varied by means of a control signal without causing any component of the control signal to appear in the output circuit of the amplifier, and the control of the gain of the said amplifier, utilizing a control signal derived from the signal channel, preferably from 50 a portion of the signal channel subsequent to the said amplifier. Further, the invention contemplates the utilization of such a device to compensate for non-linearity of apparatus with which 55 the device is employed. It will be understood, therefore, that the present disclosure is merely exemplary and is not intended to limit the scope of the invention.

I claim:

1. In an electrical signaling system, an input circuit, an output circuit, signal amplifying means connected between said input circuit and said output circuit constructed and arranged to transfer signals over a wide frequency range, means for 60 deriving a control signal from one of said circuits, signal amplifying means for said control signal constructed and arranged to operate over said frequency range, means for applying the amplified control signal to said first amplifying means 65 to control the gain thereof, whereby the gain of said first signal amplifying means varies instantaneously with the amplitude of the signal in said circuit at the point where the control signal is derived, and means for preventing said control 70

75 derived, and means for preventing said control 75

- signal or any component thereof from appearing in said output circuit.
2. In an electrical signaling system, an input circuit, an output circuit, signal amplifying means connected between said input circuit and said output circuit constructed and arranged to transfer signals over a wide frequency range, means for deriving a control signal from said output circuit, signal amplifying means for said control signal constructed and arranged to operate over said frequency range, means for applying the amplified control signal to said first amplifying means to control the gain thereof, whereby the gain of said first signal amplifying means varies instantaneously with the signal in said output circuit, and means for preventing said control signal or any component thereof from appearing in said output circuit.
3. In an electrical signaling system, a signal channel including an amplifier having an input circuit, an output circuit, a gain control circuit, and means for preventing a gain control signal from appearing in said output circuit, an amplifier for supplying a control signal to said gain control circuit, both of said amplifiers being constructed and arranged to transfer signals over a wide frequency range, and means for deriving a control signal from the signal channel and for applying said signal to said last-named amplifier, whereby the gain of said first amplifier varies instantaneously with the amplitude of the signal in said channel at the point where the control signal is derived.
4. In an electrical signaling system, a signal channel including an amplifier having an input circuit, an output circuit, a gain control circuit and means for preventing a gain control signal from appearing in said output circuit, an amplifier for supplying a control signal to said gain control circuit, both of said amplifiers being constructed and arranged to transfer signals over a wide frequency range, and means for deriving a control signal from the signal channel at a point subsequent to said first-named amplifier, and for applying said signal to said last-named amplifier, whereby the gain of said first amplifier varies instantaneously with the amplitude of the signal in said channel at the point where the control signal is derived.
5. In an electrical signaling system, a signal channel including an amplifier having an input circuit, an output circuit, a gain control circuit, and a pair of signal transfer paths adapted to balance out a control signal passing therethrough, an amplifier for supplying a control signal to said gain control circuit, both of said amplifiers being constructed and arranged to transfer signals over a wide frequency range, and means for deriving a control signal from the signal channel and for applying said signal to said last-named amplifier,
- whereby the gain of said first amplifier varies instantaneously with the amplitude of the signal in said channel at the point where the control signal is derived.
6. In an electrical signal system, a signal transfer channel including a signal amplifier, said amplifier including a plurality of space discharge devices each having an input circuit, an output circuit, and an effective mutual conductance, the mutual conductance of each of said space discharge devices being dependent upon the voltage in the input circuit of the respective discharge device, means for applying an input signal to said signal amplifier, means for deriving an output signal from said amplifier, another space discharge device having an input circuit and an output circuit, an impedance having a voltage thereacross in said input circuits and said output circuits, for establishing said voltage in each of said input circuits and each of said output circuits, means for deriving a control signal from said channel, and means for applying said control signal to the input circuit of said other space discharge device.
7. In an electrical signal system, a signal transfer channel including a signal amplifier, said amplifier including a plurality of space discharge devices each having an input circuit, an output circuit, and an effective mutual conductance, the mutual conductance of each of said space discharge devices being dependent upon the voltage in the input circuit of the respective discharge device, means for applying an input signal to said signal amplifier, means for deriving an output signal from said amplifier, another space discharge device having an input circuit and an output circuit, an impedance having a voltage thereacross in said input circuits and said output circuits, for establishing said voltage in each of said input circuits and each of said output circuits, means for deriving a control signal from said channel, and means for applying said control signal to the input circuit of said other space discharge device.
8. In an electrical signal transfer system comprising apparatus having an inherent non-linear output-input response characteristic, the method of compensating for the non-linearity of said apparatus which consists in passing the signal through a signal channel including an amplifier, deriving a control signal from the signal channel having the same frequency characteristics as the signal in the channel, and utilizing said control signal to vary the instantaneous gain of said amplifier in complementary relation to the non-linear response of said apparatus, to thereby obtain over-all linear response of said system.
